APPARATUS FOR FORMING SAND MOLDS

Frank P. Gill, Cleveland Heights, Ohio

Application August 12, 1935, Serial No. 35,692

5 Claims. (Cl. 22—24)

This invention relates to molding and, more especially, to a novel method and apparatus for forming sand molds for the production of cast metal articles.

5 The invention has to do more particularly with a novel method and apparatus for forming green sand molds which have one or more undercut grooves in the wall of the mold cavity, and which are used for the production of cast metal articles having one or more corresponding projections thereon such as brake drums having annularly extending ridges or fins. Such projecting ridges or fins are an important feature of cast metal brake drums and have heretofore been provided thereon by machining grooves in an annular surface of the drum to leave such ridges or fins upstanding. The machining of the cast metal brake drums to provide the desired ridges or fins has involved considerable additional expense in 10 the way of excess metal contained in the castings and in the way of labor and machine operations. By my novel method and apparatus, as will be hereinafter more fully explained, the sand mold is provided with one or more undercut recesses or grooves whereby the desired projections 15 or ridges are cast integral on the brake drum or other article being produced.

It is therefore an object of the present invention to provide a novel method of molding wherein in the cavity of a green sand mold is extended by removing sand from the wall of the cavity and thereby forming an undercut recess or groove 20 therein.

Another object of the invention is to provide 25 a novel method of molding involving the forming of a green sand mold with a cavity therein having substantially the shape of the body of the casting desired and removing sand from the wall of the cavity and thereby forming undercut recesses or grooves therein corresponding with 30 projections or fins desired on the casting, and smoothing the sand in and adjacent the recesses or grooves being formed.

Still another object of this invention is to provide 35 a novel method of molding wherein the forming of the undercut grooves or recesses is accomplished by the action of a cutter which removes sand from the wall of the mold cavity, and the smoothing of the sand in the grooves or recesses is accomplished by rolling.

A further object of the invention is to provide a 40 novel method of molding comprising the forming of undercut grooves or recesses in the wall of a mold cavity and meanwhile supporting the sand

of the wall adjacent the point at which the undercut grooves or recesses are being formed.

It is also an object of this invention to provide novel apparatus for forming undercut grooves or recesses in the wall of a sand mold, 5 comprising a cutter for removing sand from the cavity wall and means operable in associated relation with the cutter for smoothing the sand in the recesses or grooves formed by the cutter.

Still another object of the invention is to provide 10 novel molding apparatus having means for removing sand from the wall of a mold cavity to thereby form an undercut groove therein, and also having means for supporting the sand of the wall during the forming of the groove.

Yet another object of the invention is to provide 15 novel molding apparatus embodying a rotatable head adapted to extend into the cavity of a sand mold, and cutting and smoothing means carried by the head for cooperation with the wall 20 of the mold cavity during rotation of the head therein.

Other objects and advantages of the invention will be apparent from the following description when taken in conjunction with the accompanying sheets of drawings wherein 25

Fig. 1 is a partial side elevational view showing 30 molding apparatus, constructed according to my invention and which may be used in practicing my novel method.

Fig. 2 is a plan view thereof.

Fig. 3 is a partial transverse sectional view of 35 the apparatus taken on line 3—3 of Fig. 2 and showing a sand mold in position on the apparatus.

Fig. 4 is a plan view of the rotatable head.

Fig. 5 is a side elevation thereof.

Fig. 6 is a partial sectional view taken through 40 the rotatable head as indicated by the line 6—6 of Fig. 4.

Fig. 7 is another partial transverse sectional view of the head taken as indicated by line 7—7 of Fig. 4.

Fig. 8 is a partial sectional view, on a larger 45 scale, showing the shape of the ridges of the smoothing roll, and

Fig. 9 is a partial plan view of the head showing another manner of mounting the cutting and smoothing means thereon.

More detailed reference will now be made to 50 the accompanying drawings for the purpose of describing my novel method and apparatus for making sand molds. It will be understood, of course, that the apparatus shown in the drawings is to be regarded as illustrative only and 55

that the apparatus and method of the invention may be varied within the scope of the appended claims.

My novel molding apparatus comprises in general a table-like support or frame 10 having thereon a rotatable head 11 which is adapted to extend into the recess of a sand mold 12 when the latter is supported on the frame, as shown in broken lines in Fig. 1 of the drawings. The 5 rotatable head, as will be explained more in detail hereinafter, is provided with an arcuate projection or segment 13 for supporting engagement with the wall of the mold cavity, and with cutting and smoothing means 14 and 15 which 10 operate with the cavity wall to form undercut grooves or recesses therein corresponding with the projections or fins desired on the castings to be produced.

The frame 10 may be constructed as shown in 20 Figs. 1 and 2 of the drawings with a box-like section 18 having supporting legs 19 at the corners thereof, and may be provided with a plate-like top 20 which is adjustably supported on the section 18. The frame section 18 may be provided substantially centrally thereof with a vertically extending bearing sleeve 21 having a shaft 22 mounted therein for operating the rotatable head 11. The bearing sleeve 21 may be supported from the sides of the frame section 18 by suitable means such as a spider-like arrangement of the ribs 23.

One end of the shaft 22 extends upwardly 25 above the plane of the top 20 through an opening 25 of the latter in the form of a spindle 26 upon which the rotatable head 11 is mounted. The lower end of the shaft 22 extends below the bearing sleeve 21 and may be connected to any suitable motor or driving device such as the electric motor 27. The motor 27 may be mounted 40 on the frame 10 in any convenient manner and may be drivingly connected to the shaft 22 by suitable means such as the beveled gears 28.

The rotatable head 11 is preferably constructed as a cast metal drum of such size and shape 45 that it will readily enter or project into the cavity 30 of the sand mold 12 when a mold box or section 31 containing such a sand mold is placed on the top 20, as shown in Figs. 1 and 3. The arcuate supporting projection 13, of the rotatable head may extend over a desired portion of the periphery of the drum and may be formed 50 as an integral part of the drum structure. The drum forming the rotatable head 11 is preferably of hollow construction for the sake of lightness and also to accommodate therein the cutting and smoothing means or devices 14 and 15. The rotatable head may be provided centrally 55 thereof with a hub or boss 33 which may be keyed or otherwise drivingly connected to the spindle 26 of the driving shaft 22.

At a point diametrically opposite the supporting projection 13 the drum may be provided with an increased body of metal to constitute a counterweight 34 for counterbalancing the projection 60 and the devices 14 and 15. The rotatable head may be supported on the driving shaft 22 by means of the shoulder engagement between the boss 23 and the shaft, as indicated at 35, or may be supported in part by such shoulder engagement and in part by engagement of the lower face 36 of the boss with the upper end of the bearing sleeve 21.

The projection 13 is provided on its arcuate outer face with a plurality of circumferentially 70 extending ridges and grooves 38 and 39 which

are spaced apart to correspond with the spacing of the fins and grooves of the brake drum or other cast metal articles to be produced. When the sand mold is supported on the top 20 and the rotatable head 11 is disposed in the cavity 5 thereof in operative relation to the cavity wall the ridges 38 are at this time pressed into the sand of the wall, and as the head is rotated, they form shallow annular grooves in the sand. As the ridges 38 of the projection 13 traverse the 10 cavity wall to form such shallow grooves, the intervening grooves 39 of the projection form corresponding relatively low ridges on the cavity wall.

At one point of the arcuate surface of the 15 projection 13, I provide a plurality of slots 40 in line with the ridges 38, and which extend through the wall of the rotatable head and communicate with the hollow interior thereof. At another point of the projection 13, I provide 20 similar slots 41 in line with the ridges 38, and which also extend through the wall of the head and communicate with the hollow interior thereof. The cutting device 14 is pivotally mounted on the rotatable head, as will be presently explained, and has portions adapted to be projected through the slots 40 into cutting cooperation with the wall of the mold cavity. Similarly, the smoothing device 15, which will be presently explained, is mounted on the head with portions 30 thereof arranged to extend outwardly through the slots 41 for smoothing cooperation with the sand of the cavity wall.

The cutting device 14 may comprise an arm 43 which is pivoted to swing on a pivot pin 44 of the 35 head, and a cutter 45 which is carried by the arm 43 and has finger-like cutting elements 46 adapted to be projected outwardly through the slots 40. The cutting elements 46 are normally held in retracted position inwardly of the face of the supporting projection 13 by means of the tension spring 48 but are adapted to be projected outwardly through the slots when the arm 43 is swung outwardly against the action of the spring by centrifugal force.

The extent to which the cutting elements 46 may be projected through the slots 40 may be limited by a stop 49 provided on the arm 43 to cooperate with an abutment 50 of the rotatable head. The stop 49 may have an adjustable contact, such as the screw 51 threaded therein, for engagement with the abutment 50.

The cutting elements 46 may be provided with relatively sharp leading edges or corners 52 which cut through the sand to form the grooves as the 55 head is rotated. These elements may also be provided with inclined faces 53 extending inwardly and rearwardly from the leading edges 52 at such an angle that the sand removed from the wall of the cavity by the cutting elements will be 60 deflected or thrown inwardly through the slots 40 and into the hollow interior of the rotatable head from which the sand may fall freely downwardly through the opening 25 of the top 20.

The grooves cut in the wall of the mold cavity 65 by the elements 46 are of substantially a cross sectional shape and size to correspond with the cross sectional shape and size of the fins and projections desired on the brake drums or other cast articles to be produced. The sand of the 70 cavity wall adjacent the undercut grooves thus formed is supported and smoothed by the projection or segment 13 of the rotatable head 11 and the sand in the grooves is smoothed by the device 15. This device comprises a roller 55 hav- 75

ing spaced ridges or flanges 56 which may be projected outwardly through the slots 41 to engage in the grooves formed by the cutting elements 46. The roller 55 is rotatably mounted on a swinging 5 arm 57 which is in turn mounted on a pivot pin 58 of the rotatable head. The arm 57 may also be provided with a stop projection 59 for limiting the extent to which the ridges 56 may be projected through the slots 41. The projection 59 10 may carry an adjustable contact screw 60 for engagement with the abutment 50.

To facilitate the removal of the sand cuttings and to prevent sand from sticking or adhering to the inner faces of the intervening bar-like portions 62 and 63 of the projection 13, I construct these bar portions with a cut-away or inclined inner face 64 as shown in Fig. 7. These inclined faces of the bar portions 62 and 63 allow the loose sand to readily fall downwardly on the inner 20 side of the rotatable head.

The ridges or flanges 56 of the smoothing roll 55 have their rims tapered to correspond in shape with the fin shape desired on the cast article to be produced, and as these rims operate in 25 the grooves they smooth the sand to the shape which the fins of the cast article are to have. The portions of the ridges which extend through the slots 41, as indicated in Fig. 8, merge smoothly with the edges of the grooves 39 on the outer 30 face of the projection 13, this being obtained by providing the fillet portions 64' on the projection.

The roller 55 is normally held in a retracted position by a tension spring 65 but is moved outwardly by centrifugal force to project the ridges 35 56 through the slots 41.

When the rotatable head is disposed in operating position within the cavity of a sand mold, such as the mold 12, the ridges 38 of the projection 13 are pressed into the sand of the cavity 40 wall, as mentioned above, and hence provision must be made for bringing the cavity wall and the projection into such cooperating relation without injury to the sand mold. While this may be accomplished in various ways, I have in this instance shown means for causing relative lateral movement between the mold and the rotatable head 11 to bring the projection 13 thereof into engagement with the wall of the cavity. This means comprises an adjustable mounting for the top 20 whereby this top, with the mold 12 supported thereon, may be moved laterally with respect to the rotatable head 11. For this purpose I may provide the underside of the top 20 with 45 spaced parallel grooves 66 into which guide projections or flanges 67 of the frame section 18 extend. At opposite ends of the top 20, I may provide depending lugs 68 which have adjusting screws 69 extending therethrough. The screws 69 engage the sides of the frame section 18 and 50 move the top 20 laterally with respect to the frame section as the screws are operated. During such shifting of the top, its movement is guided by the projections 67 engaging in the parallel groove 66.

The top 20 may be provided with means for locating the mold section 31 thereon, such as the projecting pins 70 which engage in the usual ears 71 of the mold section when the latter is placed on the top. The top may also be provided with an annular member 72 extending around the 55 opening 25 and of such cross sectional shape as to cooperate with this portion of the sand mold.

In the use of my molding apparatus and in carrying out my novel mold forming method, the mold 12 is first formed in the mold section 70 75 31 and the mold section is then placed on the

top 20 for the grooving operation. In forming the mold 12 the sand is packed around a pattern which has a shape corresponding substantially with the shape of the body portion of the brake drum or other article to be produced. The withdrawal of the pattern from the sand leaves a smooth sided substantially cylindrical mold cavity 30 therein. When the mold is placed on the top 20 in the position shown in Figs. 1 and 3 the rotatable head 11 extends into the cavity 30 while 10 the portions of the mold around the edge of the cavity engage the annular member 72. By rotating the screws 69 the top 20, with the mold thereon, is shifted laterally with respect to the rotatable head 11 and the projection 13 is thereby 15 brought into engagement with the wall of the cavity and the ridges 38 of the projection are pressed into the same.

The apparatus is now in readiness for the motor 27 to be started, and when started it operates 20 to rotate the head 11 at relatively high speed. Initial rotation of the head causes the ridges and grooves 38 and 39 of the projection 13 to form corresponding grooves and ridges on the inner surface of the wall of the mold cavity. As the 25 speed of rotation of the head increases centrifugal force acts on the cutting device 14 and causes the cutting elements 46 to be projected outwardly through the slots 40. Rotation of the head with the cutting elements thus projected causes 30 the elements to cut grooves in the side wall of the mold cavity.

As the speed of rotation of the head increases further, the smoothing device 15 is swung out by centrifugal force to cause the ridges 56 of the 35 roller 55 to be projected through the slots 41 and into smoothing cooperation with the grooves which have been formed by the cutting elements 46. During the cutting and smoothing of the grooves by the respective devices 14 and 15, the projection 13 remains in contact with the wall of the mold cavity and supports the sand thereof against loosening and crumbling.

After such rotation of the head 11 the driving motor 27 is stopped and the screws 69 are operated 45 to move the top 20 in a direction to separate the projection 13 from the wall of the mold cavity, whereupon the mold may be lifted from the top 20 without injury to the undercut grooves which have now been formed in the cavity wall. 50

It is not necessary to my invention that the cutting and smoothing devices be separately mounted on the rotatable head, but may be carried by the same supporting member or arm. For example, cutting and smoothing devices 14' and 55 15', which are of similar construction to corresponding devices 14 and 15, may be both mounted on a single pivoted arm 74 to be projected from the rotatable head 11 for cooperation with the wall of a mold cavity.

From the foregoing description and the accompanying drawings it will now be readily understood that I have provided a novel apparatus and method for forming grooved sand molds for the production of cast metal articles having 65 projections thereon such as cast metal brake drums having annularly extending ridges or fins thereon. It will be understood further that by my novel method and apparatus sand is removed from the wall of the mold cavity to form the 70 undercut grooves or recesses and the sand in and adjacent the grooves is supported and smoothed so that after the grooving operation the mold will have a desired smooth and accurate shape.

While I have illustrated and described my 75

molding apparatus and method in a somewhat detailed manner, it will be understood of course, that I do not wish to be limited to the precise details of construction and steps of procedure herein described, but regard my invention as including such changes and modifications as do not constitute a departure from the spirit of the invention and the scope of the appended claims.

I claim:

- 5 1. In molding apparatus the combination of a rotatable head adapted to extend into the cavity of a sand mold and having a ridged segment in contact with the wall of the cavity during rotation, means for rotating said head, said segment having slots therein in line with the ridges thereof, and cutting elements adapted to be projected through said slots for forming grooves in the cavity wall.
- 10 2. In molding apparatus the combination of a rotatable head adapted to extend into the cavity of a sand mold and having a ridged segment in contact with the wall of the cavity during rotation, means for rotating said head, said segment having slots therein in line with the ridges thereof, and cutting elements adapted to be projected through said slots for forming grooves in the cavity wall.
- 15 25 3. In molding apparatus the combination of a rotatable head adapted to extend into the cavity of a sand mold and having a ridged segment in contact with the wall of the cavity during rotation, means for rotating said head, said segment having slots therein in line with the ridges thereof, and cutting elements adapted to be projected through said slots for forming grooves in the cavity wall, and a roller having ridged portions adapted to be projected through said slots for smoothing the grooves.
- 30 4. In molding apparatus the combination of a

rotatable head adapted to extend into the cavity of a sand mold and having a ridged segment in contact with the wall of the cavity during rotation, means for rotating said head, said segment having slots therein in line with the ridges thereof, and shiftable members on said head centrifugally operable in succession, one having teeth adapted to be projected through said slots for forming undercut grooves in the cavity wall and the other having a roller provided with ridge portions adapted to be projected through the slots for smoothing the grooves.

4. In a molding apparatus, the combination of a rotary head adapted to extend into the cavity of a sand mold, said head having a segment projecting beyond the periphery of the head, for contact with the sand wall of the cavity during rotation of the head, said segment being slotted, cutters movably mounted on the head and movable through some of the slots in the segment to cut grooves in the said wall during said rotation, and smoothing devices carried by the head and movable outwardly into said grooves through other slots in the segment.

5. The combination stated in claim 4, the smoothing devices comprising a roller having ridges which project through said other slots and into grooves as the head is rotated.

FRANK P. GILL. 30
